CLAIM

The ornamental design for a holster belt as shown and described.

DESCRIPTION

FIG. 1 is a top front perspective view of a holster belt in accordance with our new design;

FIG. 2 is a bottom, rear, perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a top, front, perspective view thereof with pockets shown in open position.

The broken lines having equal dash lengths in the drawings illustrate structure and/or features that form no part of the claimed design. The dash-dot-dash lines in the drawings illustrate stitching that forms no part of the claimed design. The holster belt is shown with a symbolic break in its length. The appearance of any portion of the article between the break lines forms no part of the claimed design.
